UNITED STATES PATENT OFFICE.

ROSALIND H. BOWER, OF SAN FRANCISCO, CALIFORNIA.

STRIKE-PLATE FOR LOCKS.

SPECIFICATION forming part of Letters Patent No. 572,859, dated December 8, 1896.

Application filed April 15, 1896. Serial No. 587,580. (No model.)

To all whom it may concern:

Be it known that I, ROSALIND H. BOWER, a citizen of the United States, residing in the city and county of San Francisco, State of California, have invented an Improvement in Adjustable Strike-Plates for Locks; and I hereby declare the following to be a full, clear, and exact description of the same.

My invention relates to an improved strike-plate for mortise-locks.

It consists of the parts and the constructions and combinations of parts hereinafter described and claimed.

Referring to the accompanying drawings for a more complete explanation of my invention, Figure 1 is a view showing my strike-plate and its attachment to the casing. Figs. 2 and 3 show the plates separated.

A represents the casing of a door.

20 B is the exterior portion of my strike-plate, which is let into the edge of the casing opposite the point where the lock is fixed in the door and has the usual projecting strike C, against which the beveled latch contacts when 25 the door is closed.

The elongated slot which extends from near the top to near the bottom of the plate B has its sides made in the form of tongues b, adapted to receive the correspondingly-shaped 30 grooves made in the edges of an independent inner plate D, or, if preferred, the tongues may be made on the inner plate and grooves upon the outer one, the object being in any case to retain the inner plate in position within 35 the outer one, having its surfaces approximately flush with those of the outer plate. This inner plate has the openings E and F made in it near the top and bottom, respectively, to receive the latch and the bolt of the 40 lock.

Along one edge of the inner plate is made a channel or slot G, and in the outer plate opposite to it is made a countersunk semicircular depression G'. The edge of the slot G 45 is also beveled to correspond with the countersunk opening, and this allows a screw to be introduced into this opening and turned down, so that its head, fitting into the countersunk opening on one side and against the beveled 50 face upon the other side, will firmly lock the two parts together. When the screw has been loosened, the inner plate is slidable within

the outer one and may be set at any desired point.

The operation will then be as follows: When 55 the lock is fitted to the door, a mortise of sufficient length is made opposite the openings into which the catch and bolt of the lock enter and of sufficient depth to receive them. The strike-plate is then fitted into the edge 60 of the door and secured by screws at the top and bottom, and the inner slideable plate is adjusted so that the slots through it coincide, respectively, with the catch and the bolt. The two plates are then locked together by 65 the screw at H, and the device remains in this condition as long as no change occurs in the relative position of the door and casing. The door or casing may either of them settle or get out of position from various well-known 70 causes, so that the bolt and catch do not coincide with the openings in the strike-plate. When this occurs, it is only necessary to loosen the screw with a screw-driver and move the inner plate up or down, as the case 75 may be, sufficiently to make the openings again coincide with the bolt and catch, after which the screw is tightened and the two are locked together. By this construction it is possible for any one in the house to keep all the locks 80 of the doors throughout the house in good working condition without the necessity of removing the strike-plate, resetting it, or cutting new mortises in the door-casing.

Having thus described my invention, what 85 I claim as new, and desire to secure by Letters Patent, is—

1. A strike-plate for mortise-locks consisting of a plate to be secured to the door-casing, having a slot formed longitudinally in 90 it wholly inside of its margins and having an outwardly-projecting strike from one edge, said plate having the vertical side walls of its slot formed with tongues, a second plate fitted to slide within the slotted portion of the first- 95 named plate and having its vertical edges grooved to receive said tongues, said slideable plate having two independent openings, one for the latch and the other for the bolt of the lock, and means for securing the slideable 100 plate in its adjusted position.

2. A strike-plate for mortise-locks consisting of a longitudinally-slotted plate, means for securing it to the casing, said plate hav-

ing tongues upon its vertical parallel sides, a second plate of less length than the channel in the outer one having grooves adapted to fit the tongues in the outer plate and openings 5 to receive the latch and bolt of the lock, a beveled channel formed longitudinally in one side of the plate, a countersunk semicircular opening in the adjacent edge of the outer plate and a screw adapted to lock the two at

any point of their adjustment with relation to each other.

In witness whereof I have hereunto set my hand.

ROSALIND H. BOWER.
